UNITED STATES PATENT OFFICE.

ROBERT D. DUNCAN, JR., OF EAST ORANGE, NEW JERSEY, ASSIGNOR TO WIRED RADIO, INC., OF NEW YORK, N. Y., A CORPORATION OF DELAWARE.

POLYPHASE-CARRIER-CURRENT BROADCASTING SYSTEM AND GENERATOR.

Application filed January 9, 1925. Serial No. 1,374.

To all whom it may concern:

Be it known that I, ROBERT D. DUNCAN, Jr., a citizen of the United States, residing at East Orange, in the county of Essex, State of New Jersey, have invented certain new and useful Improvements in Polyphase-Carrier-Current Broadcasting Systems and Generators; and I do hereby declare the following to be a full, clear, and exact description of the invention, such as will enable others skilled in the art to which it appertains to make and use the same.

In high frequency carrier current broadcasting systems superimposed on electric power and lighting lines—popularly known as wired radio—there has heretofore been employed only single phase carrier frequencies. Most power transmission systems, however, are of the poly-phase type—usually three-phase. It is possible under favorable conditions to distribute a single phase carrier over a poly-phase system, but practical experience has indicated that this cannot be done consistently enough for commercial broadcasting on a large scale.

Almost from the very beginning of the extensive research work which has been carried on in the wired radio broadcasting field it has been realized that more even and satisfactory carrier current distribution could be effected on poly-phase power lines by the use of poly-phase carriers, but in so far as it has been possible to ascertain, there has heretofore been no known generator of poly-phase high frequency oscillations of a practical character. The present invention is directed in part to such a generator and, in part, to a wired radio broadcasting system of the poly-phase type and, more specifically, to a system wherein single phase high frequency oscillations are converted into poly-phase high frequency oscillations and superimposed upon the low frequency power currents on a poly-phase power transmission line.

The poly-phase system and generator herein dealt with are developments based, in part, upon the method of producing phase displacement disclosed on pages 352 and 353 of a publication entitled "Wireless Telegraphy," by Dr. J. Zenneck, McGraw-Hill Book Company, Inc., 1915, under the caption, "Production of any desired phase differences with undamped oscillations," wherein it is shown that between two loosely coupled res-

onant circuits, the currents are 90° out of phase and that a circular rotating magnetic field may be produced by two coils having equal magnetic fields with coincident magnetic centers and axes at right-angles and wherein the currents are 90° out of phase.

In accordance with the preferred embodiment of this invention single phase high frequency oscillations are produced by means of a master vacuum tube oscillator; and high frequency currents of the master oscillator frequency, but with a phase difference of 90° are produced by loosely coupling two resonant circuits, one of which is supplied with high frequency current by the master oscillator. With the circular magnetic field thus produced in the manner hereinbefore referred to from the single phase oscillations generated by the master oscillator, a carrier current of any number of phases may be produced by arranging a corresponding number of coils in the rotating magnetic fields with their axes at the proper angular relation to each other. In practise the three-phase or other poly-phase carrier thus produced is amplified, modulated and impressed upon the power transmission lines at the central power station or sub-station as may be convenient, and thus distributed over the power network.

The invention will be more clearly understood from the following detailed description, in conjunction with the accompanying drawings, in which

Fig. 1 is a schematic circuit diagram illustrating the underlying principles whereby single phase oscillations are converted into poly-phase oscillations.

Figs. 2 and 3 are schematic circuit diagrams serving to illustrate alternative connections of the coils in which the poly-phase currents are generated to the power transmission lines, and

Fig. 4 is a circuit diagram of a substantially complete three-phase wired radio transmitter.

In the schematic diagram of Fig. 1—1 is a single phase high frequency oscillator of any type and may conveniently be a vacuum tube oscillator. This is referred to as the master oscillator and is coupled, through a transformer 2, to a tunable circuit including the secondary winding 6, an inductance 5, coil 4 and variable condenser 3. The tunable circuit 3, 4, 5, 6 is loosely cou-

pled to a secondary circuit comprising the variable condenser 7, coil 8 and inductance 9—the coupling between the circuits being effected through the variably coupled inductances 5 and 9.

It is found that when the circuits 3, 4, 5, 6 and 7, 8, 9 respectively are quite loosely coupled and the latter tuned exactly or approximately to the frequency of the master oscillator, the currents in these two circuits are approximately or exactly 90° out of phase. In some cases it is found that circuit 7, 8, 9 must be tuned quite exactly to the master frequency while in other cases better results are obtained when this circuit is more or less detuned with respect to the master frequency. Circuit 3, 4, 5, 6 is not necessarily tuned to the master frequency but may be so. Coils 4 and 8 are so disposed with relation to each other that their axes are at right angles and their centers of magnetic flux are coincident. The center of magnetic flux is indicated on Fig. 1 as a point in each coil which is centrally located with respect to the circumference and the longitudinal extremities. It may be demonstrated that if the currents in the coils 4 and 8 are 90° out of phase with each other and the magnetic fields of the coils are equal, the combined magnetic field will rotate about the coincident centers of magnetic flux and the result will be the same as in the case of a single coil rotating about its own center of magnetic flux. In other words the resultant magnetic field is the same as in a dynamo-electric machine having a rotating field.

Three coils 10, 11, 12 are shown having their planes intersecting at angles of 60° and their centers of magnetic flux coincident with that of the coils 4 and 8. These coils being wound in the proper direction and being disposed in the rotating magnetic field will have generated in them currents which are 120° apart and if the terminals of each coil are connected together in star or delta as indicated in the circuits of Figs. 2 and 3 and also connected to a load circuit such as a three-phase power transmission line comprising conductors 16, 17 and 18, three-phase high frequency currents are generated in these coils and impressed upon the three-phase power transmission lines. Condensers 13, 14, 15 are inserted in the power lines for the purpose of preventing the low frequency power currents being short circuited through the coils 10, 11, 12 and furthermore, function to tune the power lines.

The transmitter diagrammatically illustrated in Fig. 4 comprises a master oscillator 1, phase displacing circuits 19 and 20, a high frequency amplifier 21 and a modulator 22. The master oscillator 1 is one of the well-known vacuum tube oscillator circuits and needs no description. This master oscillator is inductively coupled through windings 2

and 6, corresponding to those bearing the same reference numerals in Fig. 1, to the tunable phase displacing circuit 19, comprising elements 3, 4, 5, 6, corresponding to the circuit 3, 4, 5, 6 of Fig. 1, and in addition, variometer 23 and ammeters 24 and 25 are included in this circuit. The secondary phase displacing circuit corresponding with secondary circuit 7, 8, 9, of Fig. 1, includes in addition to elements 7, 8, 9, a variometer 26 and an ammeter 27. The ammeter 25 is common to both circuits 19 and 20. Coils 4 and 8 of Fig. 4 are arranged with respect to each other in the same way as coils 4 and 8 of Fig. 1.

Coils 10, 11, 12 of Fig. 4 correspond with the coils having the same reference numerals in Fig. 1. These coils should be physically disposed with respect to coils 4 and 8 in the same manner as described in connection with Fig. 1, that is to say they should be so arranged that three-phase currents will be generated in them by the rotating magnetic field about coils 4 and 8. Coils 10, 11, 12 are shown connected in star and are included in the input circuit of three-parallel vacuum tube amplifiers 28, 29, 30. It will be noted that the common terminal of these three coils is connected to the grounded filaments while the remaining terminals are connected to the grids of tubes 28, 29 and 30 respectively. The plate-filament or output circuits of amplifier tubes 28, 29, 30 include inductances 31, 32, 33, respectively, each in series with a condenser 34, 35, 36. These inductances are coupled respectively to coils 37, 38, 39 which are connected in delta to the transmission lines 16, 17, 18, and through condensers 13, 14, 15. Variometers 40, 41 and 42 are connected in series with the coils 37, 38, 39 respectively, their functions being to tune the transmission lines.

The modulator 22 by means of which the high frequency carrier currents are modulated in accordance with speech, music or other sound waves to be broadcast comprises three parallel amplifier tubes 43, 44 and 45. The parallel input circuits of these tubes includes the secondary winding of a transformer 46 in the primary circuit of which is a microphone 47 and a battery 48. A grid biasing battery 49 may also be inserted in the input circuit of the modulator tubes.

A generator 50 supplies direct current to the plate circuits of all the vacuum tubes. A high inductance coil 51 functions in the well known manner to effect plate potential variations at the amplifier tubes in accordance with the audio frequency variations impressed on microphone 47. Three radio frequency choke coils 53 are inserted respectively in the plate-current supply circuits of the amplifier tubes 28, 39, 30. These coils serve to prevent the shunting of high fre-

quency currents from the output side of the amplifier through the modulator tube.

In operation variometers 23 and 26 in circuits 19 and 20 respectively, and condenser 7 are ordinarily adjusted until the ammeters 24 and 27 show the same reading. If, under these conditions and with the proper degree of coupling between inductances 5 and 9 the reading of ammeter 25 should be equal 10 to $\sqrt{2}$ times the reading of either of the other ammeters.

In the particular system of Fig. 4 modulation is effected at the amplifier tubes, rather than at the oscillator tube. Modulation is effected in this case through diversion of current from the plate circuit of the amplifier tube through the parallel plate circuit of the modulator tubes. It is to be understood that the three-phase transmission 15 line 16, 17, 18 is connected to a source of low frequency three-phase power supply and that it extends to local distributing points where the phases are branched off—usually through stepdown transformers—to the 20 various power and lighting subscribers and that these subscribers or some of them are provided with receiving sets which are connected through lamp sockets or otherwise to these respective branches. It will further- 25 be understood that each branch line, except in special cases, conducts only one of the three-phases of each frequency, that is, the power frequency and carrier frequency.

It is apparent that the invention herein disclosed is applicable for the production 35 of poly-phase high frequency carrier currents having any number of phases, at least within the limit of the number of phases employed in power transmission systems.

40 I claim:

1. A broadcasting system comprising a poly-phase electric power transmission line, a source of poly-phase high frequency carrier current connected to said power transmission line, means for modulating said carrier current in accordance with signals to be transmitted over said power transmission line, and receiving apparatus responsive to the modulated carrier current and operative 45 to reproduce said signals, said receiving apparatus being connected to said power transmission line.

2. A broadcasting system comprising a poly-phase electric power transmission line, a source of poly-phase high frequency carrier current, the phases of said carrier current being the same in number as those of said line, said source of carrier current being so connected to said line that each power 55 phase has superimposed upon it one of the phases of said poly-phase high frequency carrier current, means for modulating said carrier current in accordance with signals to be transmitted, and a plurality of receiv-

ing stations each of which is connected to one phase only of said transmission line, there being one or more of said receiving stations connected to each phase of said transmission line, said receiving stations each comprising apparatus responsive to modulated carrier currents to reproduce signals transmitted thereby over said transmission line.

3. The combination with an electric power distribution system comprising a poly-phase power transmission line, of a poly-phase carrier current generator connected to said line, a plurality of receiving stations connected to said line, each of said receiving stations comprising means responsive to modulated high frequency carrier currents received from said line to reproduce sound waves corresponding to the modulations of said carrier currents, said generator comprising a single-phase master oscillator in combination with phase displacing circuit connections whereby high frequency currents having a phase difference of approximately 90° are produced, circuit means utilizing said last mentioned currents for producing a rotating magnetic field, a plurality of coils situated in said rotating magnetic field and arranged to have poly-phase high frequency currents induced in them by said magnetic field, a poly-phase vacuum tube amplifier having an input circuit including said coils and an output circuit connected to said power transmission line, and means for modulating the high frequency carrier currents in accordance with signals to be transmitted.

4. The combination with an electric power distribution system comprising a three-phase power transmission line, of a three-phase high frequency carrier current generator comprising a source of single phase high frequency oscillations, a pair of tunable loosely coupled circuits at least one of which is tuned to the frequency of said single-phase oscillations and one of which is supplied with single-phase oscillations from said source, each of said tunable circuits including a coil, the centers of magnetic flux of which are coincident and the axes of which are at right angles, the magnetic fields of said coils being substantially equal, three secondary coils having their axes angularly displaced by approximately 60° , said secondary coils being situated in said magnetic field, the arrangement being such that three-phase high frequency carrier currents are induced in said secondary coils, means for amplifying and impressing said three-phase carrier currents on said power transmission line, and means for modulating said carrier currents in accordance with signals to be transmitted.

In testimony whereof I affix my signature.
ROBERT D. DUNCAN, JR.
